METAL CONTAINER SIDE SEAM PACKING
STRIP APPLYING APPARATUS

Paul E. Pearson, Chicago, Ill., assignor to Continental Can Company, Inc., New York, N. Y., a corporation of New York

Application December 27, 1940, Serial No. 371,974

12 Claims. (Cl. 113—7)

The invention relates generally to the manufacture of metallic containers having solderless side seams wherein non-metallic seam packing strips are included, and it primarily seeks to provide a novel apparatus for applying said packing strips.

It has been proposed, heretofore, to form metallic containers having well known lock and lap side seams with non-metallic packing strips disposed so as to be bent or folded into the hooks interengaging to form the locked portion of the seams and to extend beyond said hooks and be included between the lapped portions of the seams. The present invention resides in the provision of novel apparatus for forming such packing strips and adhesively uniting them with edge portions of successively presented container body blanks so that as said blanks are formed into containers the packing strips will be positioned in the side seams as stated. An example of a form of container including a packing strip in the solderless side seam is illustrated in U. S. Letters Patent 2,171,711, issued to Walter G. Plumb and Herbert Schrader on September 5, 1939.

An object of the invention is to provide an apparatus of the character stated wherein the container blanks are successively presented at the strip applying station, and in which means is included at the strip applying station for punch forming individual packing strips and adhesively affixing them to the successively presented blanks.

Another object of the invention is to provide an apparatus of the character stated wherein the packing strips are punch formed from a web of paper bearing a heat fusible adhesive on one face thereof, and means is provided for applying heat to the strips to render the adhesive thereon tacky and also means for pressing the tacky faces of the formed and heated strips in proper position against the individually presented blanks.

Another object of the invention is to provide an apparatus of the character stated wherein the strip forming means includes an indexed rotor having a plurality of punches projecting therefrom to be successively presented at the punching position and at a position for applying the punched strips to successively presented blanks, suction control means for attaching formed strips to the punches at the forming position and for releasing said strips at the applying position, and means for directly applying heat to the exposed surfaces of the strips attached to said punches while they are passing to said applying position.

Another object of the invention is to provide an apparatus of the character stated in which the punches serve to form the strips to carry them to the applying position, and to press the tacky strips against the successively presented blanks at said applying position.

Another object of the invention is to provide an apparatus of the character stated in which is included means for detecting the absence of a packing strip on any given successively presented container blank and for ejecting such defective or incomplete blanks from the apparatus.

With the above and other objects in view that will hereinafter appear, the nature of the invention will be more clearly understood by following the detailed description, the appended claims, and the several views illustrated in the accompanying drawings.

In the drawings:

20 Figure 1 is a fragmentary side elevation illustrating the invention as embodied in a container body making machine.

25 Figure 2 is a vertical cross section of the machine portion illustrated in Figure 1, the section being taken at the position of the packing strip applying station.

Figure 3 is a fragmentary vertical cross section taken on the line 3—3 on Figure 1.

30 Figure 4 is a fragmentary vertical cross section taken on the line 4—4 on Figure 1, the cover of the turret drive housing being removed.

Figure 5 is an enlarged detail vertical cross section through the turret.

35 Figure 6 is a detail horizontal section taken on the line 6—6 on Figure 4.

Figures 7, 8 and 9 are somewhat diagrammatic vertical cross sectional views respectively illustrating the positions of the turret bars at the strip forming and applying positions just before the projection of the strip forming, carrying and applying bars, at the maximum projection of said bars, and just after retraction of said bars.

40 Figure 10 is a fragmentary sectional view illustrating one of the vacuum control valves shifted to the vacuum breaking or atmospheric air admitting position.

45 Figure 11 is a fragmentary end view illustrating the paper web feeding and cutter bar aligning mechanisms.

50 Figure 12 is a detail vertical section taken on the line 12—12 on Figure 11.

Figure 13 is a vertical longitudinal section taken on the line 13—13 on Figure 11.

55 Figure 14 is a vertical cross section taken on the line 14—14 on Figure 12.

Figure 15 is a plan view of the parts illustrated in Figure 12.

Figure 16 is an enlarged fragmentary sectional view taken on the line 16—16 on Figure 12.

Figure 17 is an enlarged fragmentary vertical cross section taken at the detector station.

Figure 18 is an enlarged side elevation illustrating the parts at the detector and blank ejector station, parts being broken away and in section.

Figure 19 is a fragmentary plan view at the position of the blank ejecting slides, the housing cover being removed and parts being broken away and in section.

Figure 20 is a fragmentary vertical cross section taken on the line 20—20 on Figure 19.

Figure 21 is a cross sectional view taken through the blank ejecting mechanism and the ejected blank receiving housing.

Figure 22 is a plan view illustrating a blank which has had a packing strip applied thereto and which has been slitted and notched in the body making machine.

Figure 23 is a view similar to Figure 22 and illustrates the same blank after the seam hooks have been bent into position for being subsequently interlocked in the formation of the side seam.

Figure 24 is an enlarged fragmentary cross sectional view illustrating the hooks of the blank shown in Figure 23 interlocked prior to the final bumping and completion of the seam.

Figure 25 is a view similar to Figure 24 illustrating the relation of the hooks in the finished seam.

Figure 26 is a view similar to Figures 24 and 25, the section being taken at the position of the lapped portion of the seam rather than through the interlocked hooks.

In the example of embodiment of the invention herein disclosed the invention is shown as embodied in one section of a container body making machine. This type of machine is well known and an example of such a body maker is disclosed in the U. S. Letters Patent to Troyer et al., 1,772,820, issued August 12, 1930.

In the type of body maker referred to, can body blanks are withdrawn one by one from a supply stack and are fed intermittently, or station to station, along suitable supporting ways. At one station the blanks are fed from a low level laterally through grain breaking rolls and are returned by these rolls to a higher level along which they are again fed step by step. At another station the lateral edges of the blanks are notched and slit in the manner illustrated in Figure 22. At another station the edge hooks which are to be interlocked in the formation of a lock and lap seam are bent in the manner indicated in Figure 23. At another station the blanks are shaped about a forming horn in a manner for bringing the hooks thereof into interlocking relation as illustrated in Figure 24, and at this same station a bumping steel engages the hooks and serves to finish the seam in the manner illustrated in Figure 25.

The particular mechanisms forming the basis of the present invention are adapted to apply packing strips to the blanks in the position illustrated in Figure 22 so that said strips will be embodied as packing elements in the side seams in the manner illustrated in Figures 24 through 26. The mechanism of the present invention also includes detecting and ejecting devices effective to eject from the machine any blanks which have not had packing strips affixed thereto.

The mechanisms forming the basis of the present invention are mounted between the grain breaking rolls and the position at which the body blanks are notched and slit. The improved body making machine as a whole in which this invention is to be embodied may be said to comprise three distinct sections, namely, a section such as is herein disclosed and which includes the packing strip applying mechanism, the blank ejecting devices, and suitable means for feeding the blanks and also for grain breaking the same after the usual custom, a second section which will comprise a standard form of body maker from the position of the notching mechanism on through the forming station, and a third section comprising a flanging mechanism for flanging the ends of the formed can bodies immediately after they are formed. As before stated the second section of this machine is conventional, and this third section, the flanging machine, is disclosed in a co-pending application filed by Paul E. Pearson on December 27, 1940, identified by Serial No. 371,975.

The herein disclosed first section of the improved body making machine, preferably assembled as an attachment to the remaining standardized and conventional parts of the body making machine, includes a base 5 which may be a separate base extending throughout this particular section of the machine only, or it may be an extension from the base of the main or body forming section of the machine. The attachment includes a bed 6 forming an extension of the bed of the main section of the machine and which is supported on frame legs 7. The bed 6 supports side housing members 8 which form extensions of the like portions of the main section of the machine and are arranged in parallel spaced relation in the usual manner. The housing members 8 support suitable slideways or guides 9, 9a for the lateral edges of the blanks 10 which are fed along the ways step-by-step, or station-by-station, by the conventional reciprocable feed bars 11 in the manner well known to all workers in the art familiar with the so-called 4-B body maker herein referred to. The blanks 10 are fed between the usual upper and lower center guide members 12. See Figures 1 and 2.

The machine attachment frame supports a blank stack 13 from which blanks are individually withdrawn from the bottom in the usual manner by a suction cup 14 mounted at the upper end of a vertically reciprocable carrier 15 which is crank and link connected as at 16 with a thrust arm 17 in turn connected with a crank 18 driven by power transmitting connections 19 from the power shaft 20. The power shaft 20 has bearings as at 21 in the gear housing 22 and is coupled as at 23 with the main power shaft 24 having bearing as at 25 in the gear housing 26. See Figure 1.

Within the gear housing 26, the main power shaft 24 is coupled in driving relation as at 27 with two axially aligned cam shafts 28 and 29, the cam shaft 28 forming a part of the attachment herein disclosed and the shaft 29 being a part of the standard body maker or the main body forming section of the composite machine herein referred to. The axially aligned shafts 28 and 29 rotate in suitable bearings 30 supported on the machine framing. See Figure 1.

The machine attachment includes a blank grain breaking station generally designated 31 at which each blank fed from the stack is fed laterally

through grain breaking rolls and is again returned, laterally onto the blank feedways at a higher level, the blank shifting means being generally designated 32 and being driven by power transmitting connections 33 from the cam shaft 28. At the blank rolling or grain breaking station each blank is stopped or registered by a rockably mounted stop member 34 which functions in a well known manner and has movement imparted thereto, for the purpose of alternately moving into position for intercepting blanks and then moving away, by cam and roller equipment generally designated 35. After leaving the grain breaking station 31 each blank is fed to an idle station generally designated 36, and at the next feed step is delivered at the packing strip applying station generally designated 37. Another idle station 38 follows the strip applying station, and the next step station, generally designated 39, is in the nature of a packing strip absence detecting station which is immediately followed by a station generally designated 40 at which all blanks which are found not to have a packing strip applied thereto are ejected. The packing strip applying mechanism mounted at station 37, and the detecting and blank ejecting mechanisms mounted at 39 and 40, are the mechanisms with which the present invention is principally concerned. See Figure 1.

At the position of station 37, the packing strip applying station, the side housing 8 at the left hand side of the machine, looking in the direction in which the blanks are fed, supports a bearing bracket extension 41 and a bearing bracket and housing extension including a gear housing portion 42 which is closed by a removable cover plate 43. A paper roll 44 is supported as at 45 opposite the packing strip applying station, and from it a web 46 having a heat fusible adhesive applied to the under surface thereof is fed. See Figures 1, 3 and 6.

The free end of the packing strip material web 46 passes between constantly driven draw rolls 47 having trunnion bearing as at 48 in the frame 49 suitably supported on the left hand side housing 8. The rolls 47 are driven through the medium of meshing pinions 50, one of which is driven by a pinion 51 on a shaft 52 rotatably supported in the frame 49 and having mounted thereon a worm wheel 53 engaged by a worm gear 54 mounted at the upper end of a vertical shaft 55 supported in the frame 49 and having a worm wheel 56 thereon driven by a worm gear 57 carried by a shaft 58 horizontally supported in the frame 49. The shaft 58 has a packing strip forming, carrying and applying bar centering member actuating cam 59 affixed thereon and also carries a feed roll actuator eccentric 60. The shaft 58 also has fixed thereon a gear 61 to which rotation is imparted through the intermediate idler gear 62 from the gear 63 secured upon the cam shaft 28. See Figures 1, 6, 12, 13, 14 and 16.

In frame extensions 64, bearings 65 are provided for a shaft 66 to which a rotor or turret 67 is keyed. The shaft 66 also has affixed thereto a Geneva or star wheel 68 within a suitable housing 69 closed by a removable cover plate 70. In order to provide for indexing of the turret or rotor station-by-station about its axis, the Geneva wheel 68 is engaged by a driving roller 71 which projects from a driving rotor 72 mounted on a stud shaft 73 and which includes the usual Geneva lock 74 and also a gear portion 75 to which rotation is imparted by a driver gear 76

78 secured upon the shaft 58. See Figures 2, 3, 4 and 6.

The turret is provided with a plurality, eight being shown, of radial longitudinal slideways 77 opening through the periphery of the turret. Each slideway has a packing strip forming, carrying and applying bar 78 slidably mounted therein, and each said bar has its radially extended extremity reduced as at 79 to conform substantially to the width of the packing strip to be engaged and applied thereby in a manner hereinafter to be described. Each bar 78 is provided with end extensions equipped with actuator rollers 80 which are received in actuator grooves 81 provided in grooved plate cams 81, one said cam being freely oscillatable about the axis of the turret at each end thereof. See Figures 2, 5 and 6.

Each bar 78 also includes a suction duct 82 which communicates with the strip engaging face of the bar through small ducts or orifices 83. Each of the bar ducts 82 constantly communicates through an elongated recess 84 with a suitable connecting duct 85 leading to a valve bore in a sleeve 86, one such valve bore and sleeve being associated with each bar 78. Each of the valve sleeves has a spring projected plunger valve 87 slidably mounted therein and each valve 87 has a cut out or clearance 88 large enough to bridge the respective port 85 and a port 89 leading to an annular duct 91 surrounding the turret shaft 66. The turret shaft 66 is provided with a central vacuum duct 92 which communicates through radial ports 93 with the annular duct 91 and through radial ports 94 with an annular duct 95 formed in one of the shaft bearings and which connects as at 96 with a vacuum pump or any other source of negative pressure (not shown). It will be noted that the projected end 40 of each valve plunger 87 engages the adjacent plate cam 81 and that each valve sleeve includes a port 87 open to atmosphere. Each port 87 is so related to the associated ducts 85 and 90 that the clearance 88 in the valve plunger will bridge and connect the ducts 85 and 90 or, in the shifted position of the valve, will connect the port 85 with the vacuum release or atmospheric air port 87 while closing off the negative pressure communication between the bar ducts 83 and the duct 92. See Figures 5, 6 and 10. The cams 81 have identical actuator grooves 88 for engaging the bar rolls 80 and determining the positions of the bars 78. Each of these grooves includes two bar projecting humps 89 spaced 90° apart in the manner best illustrated in Figures 7, 8 and 9 of the drawings. These cam humps serve to simultaneously project and retract two bars, one such bar positioned in a packing strip pick up station or position and the other positioned in a packing strip applying station or position as illustrated at the center left and center bottom respectively in Figures 7 and 8.

At the packing strip applying station the can body blanks are engaged at their side edges by abutment guides 100, and the left hand edge of the blank which is to subsequently overlap in interlocking hook relation with the opposite side edge of the blank extends at 101 between an overlying guide 102 and the left hand abutment guide 100. See Figure 5. The packing strip forming, carrying and applying bars are normally retracted but, as previously stated, these bars are projected at two stations or index positions, one at which a packing strip is formed and at-

tached to the bars and another at which the packing strips, carried by the bars from the forming station or position, are pressed against or applied to the extended edge portion 101 of the blanks. In order to accomplish this purpose the cams 81 are oscillated through approximately 45° about the axis of the turret. During each rest interval of the turret the cams are moved counter-clockwise to effect a projection and retraction of the two bars positioned at the forming and applying positions or stations, and after this projection and retraction of the bars is effected, the cams are moved back to their initial position during the indexing of the turret so that the movement of the cams in the direction of movement of the turret has no effect on the positions of the bars. See Figures 3, 5, 7, 8 and 9.

In order to impart the desired oscillatory movement to the cams 81, each cam has an actuator plate 103 adjustably secured thereon at 104 and connected by a pitman 105 attached thereto as at 106 with an actuator crank 107 mounted on a shaft 108 supported in the frame portions 41 and 42. The shaft 108 is rocked by a crank 109 having a roller projecting therefrom and engaged with an actuator cam 110 secured upon the shaft 28. See Figures 2, 3 and 6.

When the reduced end of each bar is projected at the packing strip forming position or station, it engages in cutting relation with the cutter edge portion 111 of a frame supported die block 112. Movement of each bar in contact with the die block 112 is opposed by a spring-pressed block 113. See Figures 2, 5, 11, 12 and 16.

The free end of the web 46 passes loosely from the draw rolls 47 over a drag feed roll 114 having a trunnion bearing as at 115 on the frame and having a ratchet disk 116 fixed thereto. A ratchet arm 117 is freely oscillatable about the axis of the roll 114 and carries a driver pawl 118 which engages the ratchet disk 116, and the arm is slot and pin connected as at 119 with a pitman and strap 120 actuated by the eccentric 60 fixed upon the shaft 58 hereinbefore referred to. In passing vertically down over the feed roll 114, the web end passes through a confining and guiding space between the block 112 and a spaced guide bar 121, and above said bar 121 the web is engaged by a drag bar 122 which is spring-pressed toward said roll as at 123. At each rotation of the shaft 58 the ratchet and pawl equipment will serve to feed a web portion below or beyond the cutting edge 111 of the die block equipment to the width of the packing strip next to be formed by projection of the then presented forming bar. See Figures 11, 12, 15 and 16.

A pair of aligning slides 124 are slidably mounted as at 125 on the framing, and each said slide includes a bar end receiving and aligning groove 126 for engaging an end of the particular bar presented at the forming station prior to its engagement with the die block cutting edge 111 so as to assure proper co-relation of these packing strip length severing parts. The slides 124 are link-connected as at 127 to crank arms 128 secured to a shaft 129 rockably mounted in the framing and to which rocking movement is imparted by a crank portion 130 having a roller engaged by the cam 59 hereinbefore referred to as mounted on the rotary shaft 58. The crank portion 130 is held against the cam by a spring plunger 131. See Figures 11, 12 and 15.

A heater sector 132 partially surrounds the turret and provides a heat zone for directly applying heat to the exposed, fusible adhesive bear-

ing faces of the packing strips carried by the radially presented turret bars. The sector 132 is composed of a plurality of individual resistance heater elements 133 suitably protected by insulation, and the sector is suspended upon rollers 134 on longitudinally disposed supporting rods 135. The rods 135 are supported at their ends in brackets 136 mounted a considerable distance in advance of and beyond the packing strip applying station so that the sector 132 can be conveniently shifted along the rods so as to uncover and render readily accessible the turret and the mechanisms associated therewith. See Figures 1, 2 and 5.

The plate cam 81 at the right hand side of the turret as viewed in Figure 6 of the drawings is equipped with a vacuum control hump 137 which is arcuately shaped and disposed for engagement with the valve plungers 87 extending from the turret toward said cam. This cam hump is normally disposed in the position illustrated in Figure 7 of the drawings when any given turret bar is presented to the packing strip pick up position illustrated at the center left in said Figure 7. In this position the cam engages the valve plunger associated with the bar at the pick up position and also with the plunger associated with the bar next to be moved in a clockwise direction to said pick up position. When the plungers are forced inwardly by this cam the valves serve to close communication with the vacuum source and open atmospheric communication through the packing strip engaging faces of the bars. See Figure 10. When the cam plates are moved counter-clockwise in the manner hereinbefore described to project the turret bars at the packing strip pick up and applying stations in the manner illustrated in Figure 8, the cam hump portion 137 will move out of engagement with the valve plunger associated with the bar at the strip pick up station and into engagement with the valve plunger at the applying station, thus rendering the vacuum effective at the pick up station to pneumatically attach a strip to the bar at said pick up station and shifting the valve plunger associated with the bar at the strip applying station to close off vacuum communication and release the strip being pressed against the cam body blank by the last mentioned bar. It will be observed by reference to Figure 9 of the drawings that continued movement of the cam hump portion 137 in the counter-clockwise direction does not alter the valve plunger positions, and it will be obvious that when the cams are moved with the turret in the clockwise direction during the next indexing of the turret, the cam hump portion 137 will return to its normal position illustrated in Figure 7.

The parts hereinbefore described are so timed with relation to the movement of the blank feeder bars 11 that each time these bars act to present a cam body blank with its lateral edge portion exposed as at 101 centrally beneath the axis of the turret, the turret is indexed to present a packing strip applying bar directly over said exposed blank portion. At the same time the paper web feeding devices feed a length of web beyond the cutting edge 111 of the die block 112 at the packing strip pick up position illustrated at the center left in Figure 5. With the parts in this position the cams 81 are moved counterclockwise in the manner hereinbefore described and the two packing strip forming, carrying and applying bars disposed at the packing strip pick up station and the packing strip applying station are projected 75 radially from the turret in the manner illustrated

in Figures 2 and 5 of the drawings. Thus projected, the bar at the packing strip forming and pick up station severs the projected length of web, and this severed length of web, forming a packing strip, is pneumatically attached to said bar. Simultaneously, the bar presented at the applying station presses the packing strip pneumatically attached thereto against the exposed edge portion of the blank presented at the strip applying station, the vacuum previously effective to attach said strip to the bar being released as the strip is so applied.

As previously stated, the packing strips, formed in the manner just described at the forming and pick up station, are carried by the bars with the heat fusible adhesive bearing surfaces of the strips exposed through the heating zone provided by the heater sector 132. By reason of this application of heat, the adhesive is in a tacky state when the packing strips are pressed against the blanks at the applying station, and the strips are thus adhesively united with or permanently attached to said blanks. As previously stated, as each turret bar is provided at the strip forming station it is perfectly aligned with the die block 112 by the reciprocable aligning slides 124, 126 just prior to the actual severing of the strips so as to assure an efficient strip severing operation. After each blank has thus had a packing strip permanently attached to the side edge portion thereof subsequently to be formed into a container body side seam, the blank is fed step-by-step through the remainder of the machine to have its side edges first slit and notched, then to have the hooks formed in the edge portions thereof, then to be formed into a tubular container body having a well known lock and lap side seam, and finally to have the ends of the thus formed container bodies suitably flanged.

As previously stated, the invention comprehends the provision of means for detecting the absence of packing strips on blanks which have been fed past the packing strip applying station, and means for ejecting such faulty blanks so as to assure against formation of can bodies the side seams of which do not include packing strips. The station immediately following the packing strip applying station is an idle station 38 as hereinbefore described. The detecting mechanisms are positioned at the next succeeding station designated 39, and the blank ejecting means is located at the following station which is generally designated 40. At the detecting station a special bracket 138 is mounted and this bracket supports a rock shaft 139. See Figures 1, 17, and 18. The rock shaft rockably supports a bell crank lever 140 which carries the conventional blank edge clamping and stopping equipment generally designated 141 and which includes an actuator roller engaged by an actuator cam 142 secured upon the shaft 28. The bracket 138 also supports a shaft 143 which rockably mounts a bell crank lever 144, one arm of which carries a roller engaged by a detector cam 145 secured upon the shaft 28, and the other arm 146 of which is normally forced upwardly so as to hold the roller against the cam by a spring plunger 147 carried by the bracket. The arm 146 removably supports a detector unit comprising a base block 148 on which is mounted a bearing member 149. See Figure 17. A detector or conductor bar 150 is pivotally supported intermediate of its ends on the bearing member 149 in position for having one end thereof overlie the edge portion of a blank presented at this station.

This overlying end portion of the conductor bar 150 carries a depending detector pin 151. The portion of the container body blank opposed by the detector pin 151 rests upon a supporting rail 152 which is suitably grounded as a part of the electrical detecting and ejecting control circuit. Movement of the detector pin toward the rail 152 is limited by an adjustable stop screw 153 which can be accurately adjusted to permit the pin 151 to move downwardly far enough to engage a blank edge portion devoid of a packing strip but not far enough to engage the supporting rail 152. The other end of the contact bar is lifted by a spring plunger 154, and this contact bar is connected in the control circuit by a screw 155 which serves as an attaching medium for the conducting wire 156. It will be obvious that during each rotation of the cam 145 the detector pin 151 will be moved into and then out of contact with the particular container body blank presented at the detecting station.

The ejecting mechanism located at station 40 includes a housing 157 having a removable cover and mounted as at 158 on the left side housing member 8. See Figures 1, 18 and 21. Within the housing a slide member 159 is constantly reciprocable transversely of the direction of feed of the blanks in a slide guideway 160, said slide being link-connected as at 161 with the upper end of a rock member 162 pivotally supported as at 163 and having its lower end equipped with an actuator roller engaged by an actuator cam 164 mounted on the shaft 28. An ejector slide 165 is slidably mounted above the slide 159 in a guideway 166, and this ejector slide moves with the slide 159 only when the latch 167 carried thereby is depressed into the path of movement of and contacts the actuator plate portion 168 carried by the slide 159, said plate 168 having a recess 169 therein for receiving the end of said latch. See Figures 17 and 18.

The latch member 167 carries a depresser roller 170 projecting from the top of the latching end thereof, and a spring 171 normally holds the latch lever in the lifted or unlatched position determined by the stop 172 formed by the projected opposite end of said latch member. The slide 165 has an opening 173 therein through which the latch 167 projects and also carries an ejector plate 174 removably secured to the end thereof and including a notched end portion 175 for normally underlying the side edge portion of a blank presented at the ejecting station.

Whenever the ejector slide 165 is latch-connected to the actuator slide 159, the blank presented at the ejecting station will be engaged by the notched end portion 175 of the slide and moved laterally far enough to be presented between constantly rotating ejector rolls 176 which will serve to eject the blank from the feedways. As each ejector blank is being moved through the rolls 176 it is caused to pass between a straightening roll 177 and an opposing steel 178 and thence into the ejector blank receiving magazine 179. The roll and steel equipment 177 and 178 serve to remove from the blank the tendency to bend imparted thereto by the rolls at the grain breaking station hereinbefore referred to, and while the blank being ejected is moving through the rolls 176, the overlying guide member 180 disposed at the ejecting station prevents upward buckling of the blank.

The means for bringing about a latching of the ejector slide with the actuator slide under control of the detector mechanism will now be de-

scribed. A solenoid 184 is mounted in the housing 157 and is connected with a suitable source of power diagrammatically illustrated at 182 which also connects with the conductor line 156 connected with the contact bar 150 in the manner hereinbefore described. The solenoid is also grounded, and thus a control circuit is completed whenever the detector pin 151 engages the bare metal of a blank devoid of a packing strip at the detecting station, said circuit being completed through the ground connection of the rail 152, the metal blank 10, the detector pin 151, the conductor bar 150, the conductor 156, the power source 182, and the ground connection of the solenoid. See Figures 18 and 19.

Whenever the solenoid is energized by completion of the circuit in the manner just above described, the core 183 of the solenoid is retracted against the compression spring 184 which engages a latch lever 185 to which the core is link-connected as at 186. The spring normally holds the latch member 185 against an adjustable stop 187. The latch member 185 includes an undercut nose portion 188 engageable by a latch nose 189 removably attached to the upper end of a vertically reciprocable member 190 which carries a roller at its lower end and is yieldably held against an actuator cam 191 secured upon the cam shaft 29. It will be obvious that the latch nose 189 is constantly reciprocated and also that it will engage the undercut nose portion 188 of the latch member 185 only when said latch member is moved into the path of travel thereof by retraction of the solenoid core in the manner illustrated in Figure 18 of the drawings.

The latch member 185 is pivotally mounted on a rocker member 192 fulcrumed intermediate of its ends as at 193, and it will be observed that the solenoid also is secured to this rocker member as at 194. A compression spring 195 normally serves to lift the end of the rocker member 192 opposite the end which carries the latch member 185, an adjustable stop screw 196 serving to determine the normal position of said rocker member.

The spring lifted end of the rocker member carries a pivotally mounted actuator finger 197 which is yieldably depressed by a compression spring 198 and which overlies the latch depressing roller 170 carried by the latch member 167. Thus each time the solenoid is energized the latch member 185 is moved over into the path of vertical reciprocation of the nose 189 and upward movement of said nose will serve to lift the end of the rocker member 192 to which the latch member 185 is attached and depress the end of said rocker member which carries the depressor finger 197, and it will be obvious that depression of the member 197 will serve to depress the latch member 167 into position for being engaged by the actuator slide thereby to cause the slides 165 and 159 to move together and effect an ejection of a blank in the manner hereinbefore described.

It will be obvious that as a blank detected as being devoid of a packing strip at the detecting station is moved from that station 39 to the ejecting station 40 it will move out of contact with the detector pin 151 and break the solenoid circuit effective to retract the core 183 and initially position the latch member 185 in the position illustrated in Figure 18. Were no means provided for retaining this initial position of the latch member 185 while the blank is being moved to the ejecting station, the rocker member 192 would not be properly actuated to effect the

latching of the slide 159 and 165 in the manner hereinbefore described. In order to provide for the delayed action necessary to permit shifting of the blanks from the detecting station subsequent to the closing of the control circuit at the detecting station and prior to latching of the slides at the ejector station, the cam 191 is provided with a dwell for holding the latch nose 189 in the position illustrated in Figure 18 during the delay interval stated. This cam includes an additional rise portion effective after the delay interval referred to to additionally lift the nose 189, the latch member 185 and the rocker member 192 for effecting depression of the finger 197 and the underlying latch member 167. During the delay interval referred to, the latch 185 is held in engagement with the partially lifted nose 189 by reason of the undercut 188 despite the fact that the solenoid energizing circuit has been broken.

The lever 162 is held against the cam 164 by a spring projected sleeve 199 supported on the pivotally mounted pin 200.

In Figure 22 of the drawings there is illustrated a blank having a packing strip 201 affixed theron. As previously stated, after the blanks having strips attached thereto leave the strip applying station they are edge notched at 202 and slit at 203 in the standard body making portion or machine section, the slits passing through both the metal and the attached strip 201 in the manner illustrated in Figure 22. At a subsequent station the hooks 204 are bent into position to be interlocked at the forming station in the manner illustrated in Figure 24, in which figure it will be observed that the packing strip folds into the seam as at 205. The portions of the packing strips which are not folded into the locked portion of the side seam extends at 206 into the lapped portions of the seams in the manner clearly indicated in Figures 22, 23 and 26. It will also be observed by reference to Figure 25 that when the interlocked hooks are bumped together at the forming station in the standard body maker, a seam locking bead 207 is struck up in position for securing the non-soldered side seam against opening under stresses tending to crush the finished container.

While it is preferred that heat be applied directly to the exposed, heat fusible adhesive bearing surfaces of the packing strips as they are being carried by the turret bars by means equivalent to the heat sector 132, the invention comprehends the application of adhesive while the strips are in transit toward the position at which they are applied and also application of heat in other ways, as by applying the heat to the blank edges rather than directly to the heat fusible adhesive bearing strips. It is also preferred to utilize the turret bars to sever packing strips from a continuous web in the manner hereinbefore described, but the invention also comprehends the picking up of individual strips at the receiving station by the turret bars however the strips might be provided at that position, as for example by a formed strip positioning magazine or the like.

It is of course to be understood that the details of structure and arrangement of parts may be variously changed and modified without departing from the spirit and scope of my invention.

I claim:

1. In apparatus of the character described, blank supporting ways, means for feeding individual rectangular metallic body blanks station-

by-station over said ways with a face exposed along substantially the full length of each blank at one extreme lateral margin thereof, a packing strip applying station, and means at said station for forming and picking up a heat fusible adhesive bearing packing strip, translating said strip through a heating zone to render the adhesive tacky, and then pressing said strip against the blank at said station along said substantially full length exposed face portion.

2. In apparatus of the character described, blank supporting ways, means for feeding individual rectangular metallic body blanks station-by-station over said ways with a face exposed along substantially the full length of each blank at one extreme lateral margin thereof, a packing strip applying station, packing strip material web supporting means at said station, means for cutting packing strips from said web having an adhesive on one face thereof, means for effecting a picking up and holding of the cut packing strips, means for treating the adhesive on each cut and held strip to condition it for adhering to a blank surface against which it is pressed, and means for bringing about placement of each cut and adhesive conditioned strip over and for applying pressure to affix it against said substantially full length exposed marginal face portion parallel to the direction of feed of each blank presented at said station.

3. In apparatus of the character described, blank supporting ways, means for feeding individual rectangular metallic body blanks station-by-station over said ways with a face exposed along substantially the full length of each blank at one extreme lateral margin thereof, a packing strip applying station, and means at said station for applying a non-metallic packing strip along said substantially full length exposed marginal face portion parallel to the direction of feed of each blank presented at said station, said last named means including means at said station supporting a web of packing strip material having heat fusible adhesive on one face thereof, means for feeding the web step-by-step, means for severing successive strip lengths from the end of said web, means for engaging said strip lengths and pressing them individually along each said blank edge face portion as it is presented at said station, and means for applying heat to each severed strip length before it is pressed against the blank to fuse the adhesive and cause said strips to be adhesively attached in the position stated.

4. In apparatus of the character described, blank supporting ways, means for feeding individual rectangular metallic body blanks station-by-station over said ways with a face exposed along substantially the full length of each blank at one extreme lateral margin thereof, a packing strip applying station, means at said applying station for causing packing strips to be formed and applied and adhesively attached along said substantially full length exposed marginal face portion parallel to the direction of feed of each blank presented at said station, said last named means including a drum mounted with its axis disposed in the direction of feeding movement of said blanks, a packing strip carrying and applying bar radially slidably mounted in and projected from the periphery of said drum in parallel relation to the strip receiving marginal blank face portion, means for indexing the drum, means for supporting a web of packing strip material having heat fusible adhesive on one

surface thereof, a die block, means for feeding the web step-by-step over the die block to expose a packing strip length beyond said block, means effective at one index position of the drum for projecting the bar relatively to the die block and in shearing contact therewith to sever the exposed packing strip length and form a packing strip and again retract said bar, means for effecting pneumatic attachment of the strip to the bar when it severs the strip, means at the position of the drum at which the bar overlies said strip receiving marginal blank face portion for again projecting and retracting the bar for pressing the bar carried strip against said blank face portion, and means for applying heat to the packing strip while it is attached to the bar to render tacky the adhesive on said packing strip so that it will adhere to the blank when pressed thereagainst.

5. An apparatus as defined in claim 4 in which there is included means movable into and out of engagement with the bar prior to engagement thereof with the die block for assuring proper alignment of said bar and block.

6. An apparatus as defined in claim 4 in which said bar projecting and retracting means includes a cam having roller and groove connection with the bar and means for moving the cam counter to the direction of indexing movement of the drum between indexing movements to project and again retract the bar a distance with and in the direction of drum movement during indexing movement of the drum to restore the cam to normal without effecting projection and retraction of the bar.

7. An apparatus as defined in claim 4 in which said bar projecting and retracting means includes a cam having roller and groove connection with the bar and means for moving the cam counter to the direction of indexing movement of the drum between indexing movement to project and again retract the bar a distance with and in the direction of drum movement during indexing movement of the drum to restore the cam to normal without effecting projection and retraction of the bar, and in which said pneumatic attachment effecting means includes a source of negative pressure communicable through ducts in the bars with the packing strip engaging faces of said bars and cam actuated valve means for rendering the negative pressure communication effective as each strip is to be picked up and until it is pressed against the receiving face of the blank and then ineffective so that suction contact with the applied strip will be released.

8. An apparatus as defined in claim 4 in which said heat applying means comprises a heater partially surrounding the drum and effective to directly apply heat to strips pneumatically attached to the bar to render the adhesive thereon tacky, and in which is included means for longitudinally slidably mounting said heater whereby it can be longitudinally displaced to render accessible said drum.

9. In apparatus of the character described, a rotor comprising a rotor body having a plurality of longitudinal equidistantly spaced radially disposed slideways opening through its periphery and a vacuum chamber in its central portion, means for indexing the rotor step distances equal to the slideway spacings, a packing strip severing carrying and applying bar radially slidable in each slideway and having an actuator roller projecting from each end thereof, a cam movable

independently of the rotor at each end thereof and having an actuator groove therein for receiving all rollers at the particular end of the rotor and two circumferentially spaced actuator hump portions in said groove one for effecting bar projections at a strip receiving position and the other for effecting bar projection at a strip applying position, means for moving said cams a distance counter to the direction of indexing movements for projecting and retracting the bars at said strip receiving and applying positions and a distance with the rotor during indexing movement to restore the cam to normal without effecting projection and retraction of the bars, ducts communicating between the strip engaging faces of the bars the vacuum chamber and atmosphere, and an individual valve associated with each bar and said ducts and shiftable for connecting the duct portions at the bar faces with atmosphere or with the vacuum chamber, and cam means for controlling the positions of said valves to render the vacuum effective as each bar is projected at the strip receiving position and to keep the vacuum effective while each bar moves from said receiving position to the applying position to there relieve the vacuum condition as the bar becomes completely projected at said applying position.

10. Apparatus as defined in claim 9 in which the valve position controlling means comprises cam means directly carried by one of said cams and engageable with certain of the valves during relative movement between said one cam and the rotor.

11. In apparatus of the character described, a rotor comprising a rotor body having a plurality of longitudinal equidistantly spaced radially disposed slideways opening through its periphery and a vacuum chamber in its central portion, means for indexing the rotor step distances equal to the slideway spacings, a packing strip severing carrying and applying bar radially slidable in

each slideway and having an actuator roller projecting from each end thereof, a cam movable independently of the rotor at each end thereof and having an actuator groove therein for receiving all rollers at the particular end of the rotor and two circumferentially spaced actuator hump portions in said groove one for effecting bar projections at a strip receiving position and the other for effecting bar projection at a strip applying position, and means for moving said cams a distance counter to the direction of indexing movements for projecting and retracting the bars at said strip receiving and applying positions and a distance with the rotor during indexing movement to restore the cam to normal without effecting projection and retraction of the bars.

12. In apparatus of the character described, a rotor comprising a rotor body having a plurality of longitudinal equidistantly spaced radially disposed slideways opening through its periphery and a vacuum chamber in its central portion, means for indexing the rotor step distances equal to the slideway spacings, a packing strip severing carrying and applying bar radially slidable in each slideway and having an actuator roller projecting from each end thereof, means for projecting and retracting the bars in said radial slideways, ducts communicating between the strip engaging faces of the bars the vacuum chamber and atmosphere, and an individual valve associated with each bar and said ducts and shiftable for connecting the duct portions at the bar faces with atmosphere or with the vacuum chamber, and cam means for controlling the positions of said valves to render the vacuum effective as each bar is projected at the strip receiving position and to keep the vacuum effective while each bar moves from said receiving position to the applying position to there relieve the vacuum condition as the bar becomes completely projected at said applying position.

PAUL E. PEARSON.
